UNITED STATES PATENT OFFICE.

JOHANNES FRANKE, OF DRESDEN, GERMANY.

TELESCOPIC STAND.

1,048,143.

Specification of Letters Patent.

Patented Dec. 24, 1912.

Application filed May 23, 1912. Serial No. 699,264.

To all whom it may concern:

Be it known that I, JOHANNES FRANKE, a subject of the Germany Emperor, and resident of Dresden, Germany, have invented certain new and useful Improvements in Telescopic Stands, of which the following is a specification.

This invention relates to an improved telescopic stand, for any appropriate purposes, which can be automatically arrested in any desired position.

The improved stand is represented on the accompanying drawing.

Figure 1 is a central section through same, Fig. 2 a cross section, on the line A—B of Fig. 1, and Fig. 3 a cross section on the line C—D of Fig. 1, while Fig. 4 shows the upper part of same in a central section, with a modification.

20 The stand comprises an outer tube 1, which is preferably closed at the bottom and at its top provided with a cap 2. Through said cap a pipe 3 projects centrally into said tube, which at its top carries also a cap 4. 25 Through the latter, a rod 5 projects centrally into said pipe, the top end of said rod being provided with a button 6. The latter lies within a central depression in the table α arranged on the top end of pipe 3. The 30 lower end of said rod carries a transverse member 7 which projects transversely through two elongated slots 8 in the lower end of said pipe. The pipe 3 terminates at the bottom in a flange 9, which again carries on its underside a central inverted cone 10. Said flange is inclosed by a movable shell 11 with closed bottom and open top, on which end its edge 12 is somewhat bent inward. Between said edge 12 and the flange 40 9 intervenes a spiral spring 13 which presses the shell always against the transverse member 7, while between said flange and the bottom of shell 11 a plurality of balls 14 are located, which project through holes 15 in 45 the walls of the shell so as to directly face the inner walls of tube 1.

The operation is as follows:—Upon the stand being put into the desired position, the load resting on top of pipe 3 depresses

the inverted cone 10, so that the balls 14 are 50 compelled to travel up the inclined walls of same, whereby they are firmly clamped between the latter and the inner walls of tube 1. To effect disengagement of the balls, it is simply necessary to exert a downward pressure on button 6, whereby shell 11 with the balls in its holes 15 is moved down and the balls are no longer clamped between cone and tube, so that pipe 3 can be freely moved up or down in tube 1. 55

Fig. 4 shows a modification of the operating means for the rod 5, by which a depression in the table α is omitted, said means consisting of a lever ε fulcrumed on a depending bracket γ of table α and pivoted to 65 the top end of rod 5, a slot being provided in pipe 3 for the passage of said lever.

I claim:

A telescopic stand, comprising in combination, a tube, an upper cap on said tube, 70 a centrally and movably arranged supporting pipe in said tube projecting from said cap and provided with slots in its lower end, a centrally guided rod in said pipe, a transverse member on the bottom of said rod to 75 project through said slots, a flange on the bottom of said pipe, an inverted central cone on the underside of said flange, a movable shell to inclose said flange and having a closed bottom and open top with inwardly 80 bent edges and holes in its walls below said flange, a spiral spring to intervene between the latter and said flange and adapted to press said shell toward said transverse member, and a plurality of balls movably 85 arranged in said shell to project through the holes therein and to face said cone on one side and the inner walls of said tube on the other side, substantially as and for the purpose set forth. 90

In testimony whereof I have hereunto set my hand in the presence of two subscribing witnesses.

JOHANNES FRANKE.
